(57) **CLAIM**

We claim the ornamental design for an enclosure for a camera, as shown and described.

DESCRIPTION

FIG. 1 is a top front perspective view of an enclosure for a camera, shown in condition of use;

FIG. 2 is a top front perspective view of the enclosure for a camera;

FIG. 3 is a top back perspective view of the enclosure for a camera;

FIG. 4 is a right side elevation view of the enclosure for a camera;

FIG. 5 is a front elevation view of the enclosure for a camera;

FIG. 6 is a back elevation view of the enclosure for a camera;

FIG. 7 is a left side elevation view of the enclosure for a camera;

FIG. 8 is a top plan view of the enclosure for a camera; and, FIG. 9 is a bottom plan view of the enclosure for a camera. The broken lines depict portions of an enclosure for a camera in which the design is embodied that form no part of the claimed design. The broken lines showing a junction box and a camera arm in FIG. 1 represent environmental structure and form no part of the claimed design.

1 Claim, 5 Drawing Sheets
